AXEL HERMANSEN, OF COPENHAGEN, DENMARK.

CONSTRUCTION OF REGENERATORS.

No. 891,991.

Specification of Letters Patent.

Patented June 30, 1908.

Application filed December 7, 1905. Serial No. 290,731.

To all whom it may concern:

Be it known that I, AXEL HERMANSEN, civil engineer, a subject of the King of Denmark, whose postal address is Amaliegade 5 37, Copenhagen, K., Denmark, have invented new and useful Improvements in the Construction of Regenerators, of which the following is a specification.

My invention relates to improvements in 10 the construction of regenerators having flue systems for the smoke of gases of combustion and the secondary air arranged in alternate superposed relation, for retort and other furnaces, and has for its object to make them 15 cheaper and easier to build than has heretofore been possible.

In known manner, is introduced the primary air, which previously heated if desired, is conducted through the grate to the gas- 20 producer; whence the gas formed passes into a combustion chamber, where it burns with the secondary air, previously heated in the regenerator, and also, in known manner, the 25 gases of combustion are utilized in heating the regenerator; the invention consisting in the special construction herein described of the regenerator.

The accompanying drawing shows, by way of example, a regenerator constructed accord- 30 ing to the present invention, as applied, to a retort furnace:—

Figure 1 is a transverse section, Fig. 2 is a 35 vertical longitudinal section through right half of the furnace, and Fig. 3 shows a stand- ard brick as used in building the regenerator.

The secondary air is introduced in front, near the bottom, into a flue, *a*, running lengthwise through the entire furnace; and, from this flue, the air is carried through horizontal 40 transverse flues, *b*, towards an inner chamber, *c*, extending lengthwise through the entire furnace; here, the air ascends and passes into transverse flues, *d*, situated at a higher level, and from these, it enters an outer chamber, *e*, therefrom continuing its route so as to 45 alternately pass towards the center of the furnace, and thence, at a higher level, towards the sides, until, finally, through flues, *f*, it is led into the combustion chamber *g*, 50 where it meets the producer-gas. Thus, the secondary air undulates or traverses to and fro, while ascending, in the form of a band as wide as the furnace is long.

The combustion gases, viz. the smoke, 55 pass up along the retorts, on the side thereof nearest to the center of the oven, and then downwards along their outer sides; thence, from the rear part of the furnace, through horizontal longitudinal flues, *A*, to a chamber, *B*, running along the front of the fur- 60 nace; here, the smoke descends and enters the front end of longitudinal flues, *C*, situated at a lower level than the flues, *A*, and conveying the smoke to a chamber, *D*, at the back of the furnace, where the smoke de- 65 scends again and enters longitudinal flues, *E*. Thus, also, the smoke undulates or trav- erses to and fro, while descending to the bottom of the regenerator, through a channel, 70 *F*, to the chimney.

From the above description, it follows that, in the regenerator, the secondary air, and the smoke, follow, each their own wide undulating path, the width of the same being, for the secondary air, equal to the 75 length of the regenerator; and for the smoke, equal to the breadth of the regenerator; the two undulating paths being so interlatticed that any flue of one system forms an intermediate layer between flues of 80 the other system.

As shown in the drawing, the wave lines followed by the smoke have a distance from wave to wave double that of the wave lines described by the secondary air; thus, any 85 secondary air-flue will, either, such as *d*, be situated between two different smoke-flues, *E*, or, such as *b*, be situated in the middle of one flue, *G*, dividing it up into two parallel superimposed branches. The two systems 90 of flues being shaped like wide bands of slight depth compared with their area of cross-section, the flues get a large surface for the transmission of heat from the smoke to the secondary air. The high efficiency 95 thus obtained in the regenerator is further increased by subdividing the undulating secondary air flues into a great number of narrow flues, which, being arranged side by side, offer a transmitting surface very 100 large in proportion to its total area of cross-section. The same principle is applied to the smoke-flues, and these are further subdivided by the secondary air-flues passing through any of them and dividing them into 105 parallel superimposed branches.

By arranging and subdividing the flue-systems as above described, the efficiency of the regenerator in transmitting heat from the smoke to the secondary air will be higher than heretofore known, for a given volume and quantity of material contained in the regenerator, so that the application of the system will mean considerably smaller working expenses or first cost, as compared with the regenerators heretofore used.

The invention is especially adapted for places where high level of the ground water prevents the flues of the regenerator from being placed very low; in such cases, a flue system according to this invention will make it possible to use a regenerator of small depth, and still have the same factor of efficiency as when using larger regenerators of the type heretofore known. The same applies also where old grate-bar furnaces are to be remodeled into gas-producer furnaces, the old fire-brick arches being retained.

Another and very essential advantage of regenerators of the system herein described is that they may be built very easily, cheaply and safely by using standard blocks, having a square perforation lengthwise of the furnace, and, at top and bottom, open sided transverse channels. A course of several such standard blocks arranged end to end and side by side, is laid, thus forming several adjacent ducts lengthwise of the furnace, which serve as flues for the smoke. Another course is laid on top of the first one, and the transverse channels in its lower surface, in combination with those in the upper surface of the first course, form flues for the secondary air; and other courses are laid in similar manner. By breaking joint in the consecutive courses, offsetting them, for instance, half a block crosswise of the furnace, intermediate spaces *c e* are left, alternately on one side and the other, each serving to connect two consecutive flues for the secondary air. Intermediate spaces *B D* are also left for connecting the smoke flues as desired, as, for instance, by making recesses in the end walls of the furnace. The flue systems thus produced possess a great surface for the transmission of heat, are of low first cost and easy to build, and, besides, are gas tight and remain so constantly. Tightness between the several blocks at their meeting ends is secured by rabbeting their ends so as to make them engage into each other. By means of such standard blocks may be built regenerators of any desired height, length and width, being a multiple of the corresponding dimensions of the standard blocks.

The capacity of the flue-systems for smoke and secondary air is determined by the width and length respectively of the re-

generator, but it may be further increased by connecting in parallel every two or three adjacent courses of flues, as is indicated on the drawing, by way of example, for every two courses of the smoke-flues. If desired, it is easy to cut out a section or belt of the system of flues for secondary air, for instance, at the rear end of the furnace, and utilize this section for heating the primary air. The standard blocks may be made long enough to contain one or more transverse channels.

What I claim as my invention, and desire to secure by Letters Patent, is—

1. A regenerator including in combination a series of tubular blocks having a single bore extending from end to end and having open sided channels extending transversely across their surfaces but not completely around the block, said blocks being arranged so that the interior bores thereof form a flue extending in one direction, and the channels thereof form a laterally closed flue separated from the first and extending at an angle thereto.

2. A regenerator including in combination a series of tubular blocks having open sided channels extending transversely across their surfaces, said blocks being arranged so that the interior bores thereof form a sinuous flue, and the channels thereof form a sinuous flue extending at right angles to the first.

3. A regenerator including in combination a series of tubular blocks having open sided channels extending transversely across their surfaces, said blocks being arranged so that the interior bores thereof form a sinuous flue, and the channels thereof form a sinuous flue extending at right angles to the first, said blocks being arranged in courses, some of which are offset sidewise to form chambers connecting the sections of the flues.

4. For building regenerators or the like, an elongated tubular block having a bore extending from end to end and having between its ends an enlarged open sided channel or channels extending transversely across the outer surface of the block but not completely around the same, and being of sufficient cross-sectional area to provide a suitable passage for the gases, such blocks being adapted to be laid with their bores connected to form one extended flue, and with their surface passages connected so as to form a second extended and laterally closed flue at an angle to the first.

5. For building regenerators or the like, a tubular block of rectangular form having a single bore extending from end to end and having between its ends enlarged open sided channels extending transversely across the upper and under surfaces of the block but not completely around the same, such channels being of sufficient cross-sectional area to provide suitable passages for the

gases, and such blocks being adapted to be laid with their bores connected so that the latter form an extended flue and their surface passages connected so as to form a second extended and laterally closed flue at angle to the first.

In witness whereof, I have hereunto signed

my name in the presence of two subscribing witnesses.

AXEL HERMANSEN.
